UNITED STATES PATENT OFFICE.

GEORGE WELLS, OF SOUTH NORWALK, CONNECTICUT, ASSIGNOR TO THE
WELLS AUTOMATIC SKIMMER COMPANY, OF SAME PLACE.

STRAINER FOR HAT-SIZING TANKS.

SPECIFICATION forming part of Letters Patent No. 630,429, dated August 8, 1899.

Application filed April 13, 1899. Serial No. 712,896. (No model.)

To all whom it may concern:

Be it known that I, GEORGE WELLS, a citizen of the United States, residing at South Norwalk, in the county of Fairfield and State 5 of Connecticut, have invented certain new and useful Improvements in Strainers for Hat-Sizing Tanks; and I do hereby declare the following to be a full, clear, and exact description of the invention, such as will enable others skilled in the art to which it appertains to 10 make and use the same.

My invention relates to hat-sizing machines, but more particularly has reference to straining devices for removing all sorts of impurities, such as hairs and particles of fur, from the tank or kettle within which the hats are dipped during the sizing operation.

The object of my invention is to provide a
strainer which shall rapidly cleanse the water
from impurities, which can be readily ad-
justed to occupy the proper position within
the tank, and which is so constructed that
there can be no forcing of the particles of fur
from the strainer itself out again into the
tank; and with these ends in view my inven-
tion consists in certain details of construction
and combination of parts, such as will be here-
inafter fully described and then specifically
be designated by the claims.

30 In order that those skilled in the art to which my invention appertains may more fully understand the construction and operation of the same, I will proceed to describe it in detail, referring by numerals of reference 35 to the accompanying drawings, which form a part of this application, and in which—

Figures 1 and 6 are vertical sectional elevations taken in planes at right angles to each other and showing my improvement as it appears when in operative position within a hat-sizing tank or kettle; Fig. 2, a detail end elevation of the clamp-sections and the strainer-supporting bar; Fig. 3, a detail perspective of the clamp-sections and said supporting-bar; Fig. 4, a detail perspective of the strainer-socket; Fig. 5, a detail plan view of a modified form of strainer, and Fig. 7 a detail plan of my preferred style of strainer.

Similar numbers of reference denote like parts in the several figures of the drawings.

Heretofore various strainer devices have

been contrived for use in connection with hat-ters' kettles, in some of which water-elevator pipes have been employed, while in others these pipes have been dispensed with and the 55 general current or evolution of the water relied upon to discharge the water through the strainer; but in all of these devices the bottom of the strainer has been perforated, so that it frequently happens that the strong 60 upward current due to the action of the steam-jets has forced the water, together with the impurities, up out of the strainer and out again into the tank; also, it is true that all kettles for sizing purposes are not alike and 65 that the steam-pipe for heating the kettles is not located in the same position or at the same angle in all instances.

My improvement aims to provide a strainer which shall take in quite a large area of the upward current within the tank due to the action of the steam-jets which are usually located in the bottom of the tank at the sides or center thereof, and I furthermore make provision by entirely closing the bottom of the strainer, whereby there can be no upward current through the strainer itself. 70 75

1 is the usual tank or kettle, and 2 the heating-pipe, which in the present instance is disposed in a coil around the bottom of the tank, 80 while communicating with this coil is the pipe 3, which rises upwardly through the water in the tank and communicates with any suitable steam source. This coil of pipe at the bottom of the tank is perforated on the inside in many places, as shown at 4, so that the live steam may be discharged into the water in the tank toward the center thereof, the result being that there is a strong upward current always rising in the tank. 85 90

5 6 are cylindrical strainers connected by a web 7, the sides of these strainers being perforated from the bottoms up to a short distance from the upper edges thereof, while the web is preferably solid. These strainers at 95 their outside portions or those portions which are most remote from each other are cut away so as to leave gates 8 9, and wings 10 11 are distended from the side edges of these gates, so as to afford contracted mouths for the purpose 100 of inducing the entrance of a large body of water within the strainers. The bottoms of

the strainers are closed and are formed by forcing inverted metal cups within the lower portions of the strainers, so that the closed portions of the cups constitute the bottoms 12 5 13 of these strainers, the stock of the strainers and cups being then forced outwardly by a suitable tool, as shown at the points 14 15, so as to firmly lock these bottom portions within the strainers. It will thus be readily understood 10 that not only are the strainers closed as against any upward current of the water, but that they are also hollow or cup-shaped at the bottom, thereby providing dead ends or spaces which prevent the water from diffusing laterally, as it otherwise would do if forced 15 against a flat surface not housed in by any sides.

Secured to the upper portion of the web 7 is a socket 16, to which is fitted a latch 17, 20 which by its gravity normally is projected within the interior of said socket.

18 19 are the complementary sections of a clamp, which are secured by means of screws 20 to the pipe 3 at any desired elevation. The 25 section 19 has depending therefrom ears 21, between which is the bar 22, which supports the strainer. This bar has an elongated slot 23 extending lengthwise thereof, and through this slot a stud 24 extends from said ears, so 30 that it will be readily understood that this supporting-bar is capable of rocking and sliding movements.

25 are leveling-screws, which are driven through the section 19 down against the upper 35 edge of the bar 22 on opposite sides of the stud 24, so that it will be clear that by the operation of these screws this bar may be leveled to a horizontal plane or may be tilted at an angle, as may be desired.

40 Sometimes it is necessary that the steam-pipe should rise upward through the tank at an angle; but in the adjustment of the strainers this may be compensated for by the manipulation of the leveling-screws 25, so that 45 the strainers may always hang vertically within the tank.

26 is a bolt carried at one extremity of the bar 22 and adapted to be inserted within the socket 16, one edge of this bolt being provided 50 with a notch 27, with which the latch 17 engages to prevent the withdrawal of said bolt accidentally.

Sometimes the pipe 3 extends at such an angle that it becomes desirable to provide for 55 the vertical disposition of the strainer when it is necessary that the latter shall always extend in the same direction within the tank, and I therefore have swiveled this bolt 26 to the bar 22 and have threaded the inner end 60 of this swiveled portion and driven a nut 28 thereon, so that when the bolt has been turned to bring the strainer into vertical disposition the tightening of the nut will hold the bolt in place.

65 In removing the strainer the rear end of the latch is depressed, thereby releasing said latch out of the socket in the bolt, and the

strainer is then lifted out of the tank in a very convenient manner by grasping the outer end of the socket.

The operation of my improvement is as follows: As the water in the tank is heated a strong upward current will arise, owing to the fact that the heating is effected at the bottom of the tank. This current is of course 75 continuous and the water containing the impurities will flow through the gates 8 9 into the strainers, the wings 10 11 serving to induce the entrance of a large body of water within these strainers. As fast as the water 80 passes into the strainers it will flow out through the sides of the same, while the impurities will sink to the bottom of the strainers, and the current in the tank cannot disturb these impurities for the reason that the 85 bottoms of the strainers are closed. It will thus be readily understood that there can be no disturbance within the strainers such as would tend to keep the impurities in constant agitation to the extent that they would be 90 carried out of the strainers after they have once been deposited within the same, and therefore the tank will be kept exceedingly free from impurities.

I prefer to make these double strainers 95 round in cross-section for the reason that the current in the tank is the least disturbed from its normal condition by a strainer of this shape, but of course I do not wish to be limited in this respect, since the strainer may 100 be made in half-cylindrical sections 29 30, as illustrated in the plan view at Fig. 5, in which instance I could dispense with the wings 10 11, the gist of my invention residing in the broad idea of providing a double strainer connected by a web and having closed bottoms, and, furthermore, in the provisions hereinbefore described for the universal adjustments of the strainer, so that it will always hang within the tank in a vertical plane. 110

Having thus described my invention, what I claim as new, and desire to secure by Letters Patent, is—

1. A strainer for a hat-sizing tank, comprising two properly-shaped sections joined 115 together by a web and perforated at the sides and having closed bottoms, in combination with a clamp secured to the steam-pipe, and means for detachably securing said sections and said clamp in vertical disposition, substantially as set forth.

2. In a strainer for a hat-sizing tank, the combination of the two cylindrical strainer-sections joined together by a web and perforated at the sides and closed at the bottoms, 125 the socket secured to said web, the clamp-sections secured to the steam-pipe which rises through the tank, the parallel ears depending from one of the clamp-sections, the bar having an elongated slot, the stud passed from 130 said ears through said slot, the leveling-screws driven through the last-named clamp-section against the upper edge of said bar on opposite sides of said stud, the notched bolt swiv-

eled to the outer end of said bar, the nut driven on the swiveled end of said bolt which latter is adapted to enter said socket, and the latch fitted to said socket and adapted to engage with the notch in said bolt, substantially as set forth.

3. A strainer for a hat-sizing tank, comprising two properly-shaped sections joined together by a web and having perforated sides and closed cup-shaped bottoms, substantially as set forth.

4. A strainer for hat-sizing tanks, comprising two cylindrical-shaped sections open at the tops and joined together at their middle portions in vertical disposition by a web and having perforated sides and closed cup-shaped bottoms, and cut down at diametrically opposite points at their upper edges and provided with wings which distend from said cut-away portions, substantially as set forth.

5. In a hat-sizing tank, the combination with the steam heating - pipe which rises through said tank, of a strainer suspended from said pipe within the tank, said strainer comprising two cylindrical sections open at the tops and closed at the bottoms and having perforated sides and joined together at the middle portions of said sides by a web, substantially as set forth.

30 6. In a strainer for a hat-sizing tank, the combination of the clamp secured to a stationary part of the tank, the strainer-supporting bar having an opening therethrough, the stud passed from said clamp through said opening, and the screw driven through said clamp against said bar on opposite sides of said stud whereby said bar may be adjusted to various horizontal planes, substantially as set forth.

40 7. In a strainer for hat-sizing tanks, the combination of the clamp secured to a stationary part of the tank, the strainer-supporting bar having an elongated slot, the stud driven from said clamp through said slot, and

the screws driven from said clamp against the bar on opposite sides of said stud, whereby said bar may have both angular and lengthwise adjustments, substantially as set forth.

8. In a strainer for a hat-sizing tank, the combination of the strainer-supporting bar, the clamp secured to a stationary part of the tank and by which said bar is supported, the bolt swiveled to the inner end of said bar, the nut driven upon a threaded end of said bar, whereby the latter may be secured in various rotary adjustments, and the strainer having secured thereto a socket within which said bolt is inserted, substantially as set forth.

9. In a strainer for a hat-sizing tank, the combination of the clamp secured to the steam- pipe and provided with depending ears, the strainer-supporting bar having therein an elongated slot, the stud driven through said ears and slot, the screws driven through said clamp against said bar on opposite sides of said stud, the bolt swiveled to the inner end of said bar and threaded at its swiveled end, the nut driven on said threaded portion, and the strainer having secured thereto a socket within which said bolt is inserted, substantially as set forth.

10. A strainer for hat-sizing tanks, comprising two properly-shaped sections open at the tops and joined together at their middle portions in vertical disposition by a web, and having perforated sides, said strainers having at their upper portions gates flanked by distending wings, which gates open at diametrically opposite points of the strainers toward the walls of the tank, substantially as set forth.

In testimony whereof I affix my signature in presence of two witnesses.
